Primary Examiner—Nelson C. Holtje*Assistant Examiner*—Robert M. Spear*Attorney, Agent, or Firm*—Armstrong, Westerman, Hattori, McLeland & Naughton**CLAIM**

The ornamental design of a container spout, as shown and described.

DESCRIPTION

FIG. 1 is a perspective view, taken from the top left of a container spout of the design of my invention showing the spout in the closed position;

FIG. 2 is a perspective view, taken from the top left thereof showing the spout in the open position;

FIG. 3 is a right side elevational view thereof, the left side elevational view being a mirror image of the right side;

FIG. 4 is a front elevational view thereof;

FIG. 5 is a rear elevational view thereof; and,

FIG. 6 is a bottom elevational view thereof.
